(57) **CLAIM**

The ornamental design for a collapsible, washable and reusable food and drink container, as shown and described.

DESCRIPTION

FIG. 1 is a top, front, left side perspective view of a collapsible, washable and reusable food and drink container showing the design in an unfilled condition.

FIG. 2 is a bottom, back, right side perspective view thereof.

FIG. 3 is a front plan view thereof, the back plan view being a mirror image thereof.

FIG. 4 is a top plan view thereof.

FIG. 5 is a bottom plan view thereof.

FIG. 6 is a right side elevational view thereof, the left side being a mirror image thereof.

FIG. 7 is a top, front, left side perspective view of a collapsible, washable and reusable food and drink container showing the design in a filled condition.

FIG. 8 is a bottom, back, right side perspective view thereof.

FIG. 9 is a front plan view thereof, the back plan view being a mirror image thereof.

FIG. 10 is a top plan view thereof.

FIG. 11 is a bottom plan view thereof; and,

FIG. 12 is a right side elevational view thereof, the left side being a mirror image thereof.

Shading lines are used to show solid structures and are not intended to indicate surface decoration.

The dotted lines shown in FIGS. 1-12 showing the spout and cap are included for the purpose of illustrating portions of the container that form no part of the claimed design.
